UNITED STATES PATENT OFFICE

RAYMOND F. RIFFLE, OF GREENSBURG, PENNSYLVANIA

ADJUSTABLE DOOR CATCH

Application filed January 22, 1932. Serial No. 588,206.

This invention relates to a catch for door locks, and in accordance with the present invention, while the improved catch may be used in architectural work where hinged doors are used, it is particularly adapted for use in the building of automobile bodies. My improved door catch is constructed so as to be readily adjusted to positively secure the door against rattling.

10 Further, my improved door catch will be found simple to construct, easy to operate and also very substantial and serviceable.

The invention together with other objects and advantages will be better understood 15 from a study of the following description, taken in connection with the accompanying drawing, wherein:—

Figure 1 is a plan view of the catch.

Figure 2 is a side elevation view thereof.

20 Figure 3 is a longitudinal sectional elevational view therethrough.

Figure 4 is an elevational view of one end of the catch.

Figure 5 is an elevational view of the 25 relatively opposite end of the catch.

Referring more in detail to the drawing, it will be seen that the embodiment of the invention therein illustrated, comprises a plate 5 adapted to be mounted on the door jamb by screws or other suitable fastening elements, the plate being provided with suitable openings 6 for accommodating such fastening elements.

Arranged upon one side of the plate 5 are spaced parallel guides 7 connected at one end by a transverse stop flange 8.

Constrained to shift longitudinally of the plate 5 is a catch member 9. As shown, the catch member 9 is of the double wedge type 40 presenting on the front face or side thereof corresponding beveled or inclined surfaces 10 separated by the transverse keeper shoulder 11.

On the beveled faces thereof the catch member 9 is provided with diagonal lubricant

grooves 12 crossing one another as they proceed inwardly from the corners of the beveled portions of the catch.

The catch 9 is shifted relative to the plate 5 and is secured at the desired adjustment 50 through the medium of an adjusting screw 13 that is threadedly engaged with a longitudinal socket 14 provided in the body of the catch member 9. The shank of the bolt adjacent its headed end is journaled in an aperture provided therefor in the transverse stop 8, and the bolt is held against longitudinal movement by reason of the stop 8 being received between the head of the bolt and a lock nut 15 threadedly engaged with the bolt. Manifestly, by rotating the screw 13 the catch member 9 will be shifted longitudinally of the plate 5, the desired adjustment of the catch being thus obtained in order to have the door latch properly engage the member 9 to prevent any rattling or loose movement of the door when closed. The member 9, will be secured at its adjusted position, by reason of the fact that subsequent to the positioning of the catch member 9 the lock nut 15 is screwed 65 relative to the bolt 13 in binding contact with the flange or stop 8.

Even though I have herein shown and described the preferred embodiment of the invention, it is to be understood that I reserve 75 the right to make all such changes to which I am entitled, I intending in nowise to limit the invention beyond the requirements of the prior art or the scope of the appended claim.

80 What is claimed is:—

In a door catch, a bolt keeper comprising a substantially broad flat plate having on one side thereof spaced parallel side flanges and an end flange connecting the side flanges at 85 one end thereof said side flanges having upper edge portions disposed at right angles to the bodies of said side flanges, a double wedge keeper constrained to shift longitudinally of said plate and provided on opposite sides 90

thereof with longitudinal grooves receiving the aforementioned edge portions of said side flanges, said keeper having an axial threaded socket extending inwardly from one end 5 thereof, an adjusting screw rotatably supported on said end flange and having threaded engagement with said socket; and said keeper having two inclined faces each of which is provided with intersecting diagonal 10 lubricant grooves.

In testimony whereof I affix my signature.

RAYMOND F. RIFFLE.
